UNITED STATES PATENT OFFICE.

GEORGE A. ROCKBURG, OF MILWAUKEE, WISCONSIN, ASSIGNOR OF ONE-THIRD TO JOHN C. KLEIST, OF MILWAUKEE, WISCONSIN, AND ONE-THIRD TO PETER PROVOST, OF MILWAUKEE, WISCONSIN.

GRAIN-HEATING DEVICE.

Application filed May 12, 1924. Serial No. 712,746.

To all whom it may concern:

Be it known that I, GEORGE A. ROCKBURG, a citizen of the United States, residing at Milwaukee, county of Milwaukee, and State 5 of Wisconsin, have invented new and useful Improvements in Grain-Heating Devices, of which the following is a specification.

This invention relates to improvements in grain heating devices, such as may be used 10 for the practice of the method disclosed in Patent No. 1,269,741, issued to Peter Provoost on a method for heating grain, June 18, 1918.

It is the primary object of this invention 15 to provide means for controlling the flow of grain through a multiplicity of channels in a device of this character. It will be understood that the heat throughout the interior of the device should be substantially 20 uniform, and that in order that the grain may be evenly treated it is very desirable that the length of time required for the passage of grain through each channel of the device shall be substantially identical with 25 the length of time required for the passage of material through every other similar channel. It has heretofore been difficult to obtain the desired uniformity, both in the heat of the drum and in the heat imparted 30 to different streams of grain passing therethrough, and the present invention contemplates means whereby very exact results are obtainable.

While ordinarily no air circulation is 35 needed or desired, it is a further object of this invention to provide for the control of moisture within the container by arranging for the possibility of a heat induced air circulation therethrough, and providing for 40 the control of such circulation.

It is a further object of this invention to provide improved means for agitating the grain during its progress through the various internal channels of the device, whereby there will occur a continual change in 45 the surfaces of the grain kernels which are presented to the heated walls of the channel.

This is somewhat difficult of accomplishment because of the tendency of the grain to wedge. A spiral course for the grain is 50 desirable but if ordinary means is used for directing the grain on such a course stoppage results. It is my object to provide for suitable control means while overcoming the above stated objection. 55

Further objects consist in the provision of a construction permitting of the inspection of the grain and ascertainment of its temperatures, and in the provision of a particular arrangement of baffle plates and supports therefor, whereby the uniform heat treatment of grain discharged through each 60 passage is assured.

In the drawings:

Figure 1 is a side elevation in partial vertical axial section of a device embodying 65 this invention.

Figure 2 is a section taken on line 2—2 of Figure 1.

Figure 3 is a section taken on line 3—3 70 of Figure 1.

Figure 4 is a detail view on an enlarged scale and in vertical section of a modified pipe construction with a special grain agitating device suspended therein. 75

Like parts are identified by the same reference characters throughout the several views.

From some source of steam supply (not shown) I lead steam alternatively through 80 either of two manifolds to a drum within which the grain is heated. Steam and condensate are exhausted from the drum by means of a return pipe. Preferably the arrangement is that indicated in the drawings, 85 and since the upper and lower steam manifolds are identical only one will be described in detail.

The supply pipe 10 from the source of steam supply has two symmetrical branches 90 10^a, each of which is again sub-divided into pipes 10^b. The pipes 10^b enter the drum at uniformly spaced 90° intervals about its circumference. The pipes 10^a and 10^b com-

prise a manifold which delivers steam evenly to all parts of the drum and permits of a uniform and balanced expansion of steam so that "jetting" is avoided. I have 5 found that where this precaution, of utilizing a manifold such as is indicated is not adopted, and where the steam is delivered directly to the drum through a single opening, it enters with such force and velocity 10 as to burn away the tubes or pipes within the drum, which are hereinafter to be described. Where the manifold above disclosed is employed no such burning away occurs and temperatures are uniform 15 throughout the drum.

The upper manifold preferably enters the drum substantially intermediate its ends, as indicated in Figure 1. The outlet pipe 11 is closely adjacent the bottom of the drum, and inasmuch as the heat tends to rise within 20 drum 12 the temperature may be controlled in the first instance by delivering steam to the drum through either the upper or lower manifold, or both.

The drum 12 is closed at its upper end by a head 13 and at its lower end by a head 14. The heads 13 and 14 are tied together by means of concentric series of pipes, as indicated in Figure 2 of the drawings. Pipes 30 32 15, nearest the center of the drum, may serve merely as tie rods to prevent the bulging of heads 13 and 14 and need not be used as grain conveying passages. Pipes 16, 17, and 18, however, comprising the three outer annular series are, in the present embodiment 35 of this invention, used as conduits for grain, whereby to subject the grain to the influence of the heat given off by steam within the drum.

The central portion of drum head 13 is 40 covered with an inverted conical cap 20 whereby grain is diverted to the pipes 16, 17, and 18. Although it is not necessary for the successful operation of the device, the 45 cap 20 may be supplied with an outlet pipe 21 controlled by a damper 22, such pipe being adapted to permit heated air to escape to an extent controlled by the damper opening.

Conforming in its greatest diameter to the 50 periphery of drum head 13 is an inverted conical hood 24 to which the grain is supplied through pipe 25. This hood confines the incoming stream of grain to the area of head 13 and, together with the similarly 55 shaped cap 20 comprises a passage of increasing capacity. Through this passage the grain is directed to the individual pipes 16, 17, and 18 in the outer annular series of 60 pipes which have been referred to above. The air exhaust pipe 21, if used, penetrates the passage between the walls 20 and 24 but is of sufficiently small diameter so as not to 65 impede the flow of grain therethrough.

The pipes 16, 17, and 18, in which the

grain is subjected to heat, are preferably so formed as to prevent any given kernels or grains from remaining in too constant contact with the walls of the pipes. To this end the walls of the pipes may be struck, or 70 otherwise indented, to form inwardly projecting protuberances 26, such as are adapted to maintain the grain in agitation. These protuberances are preferably not round in elevation but are elongated transversely of 75 the tube. They are made as by striking the tube with a cold chisel or like tool, having a relatively sharp transversely extending edge. The protuberances are so located in staggered 80 relation upon opposite sides of the tube that wherever there is a protuberance upon one side no protuberance will be found diametrically opposite. In this way any such constriction of the tube as might produce a 85 stoppage is avoided.

Usable either with or without tubes formed as above indicated is a central wire 30 formed at its upper end with a loop 30' to engage the upper end of the tube. The wire is provided at intervals with a series of 90 bends comprising lateral projections, and the bends are so made as to project laterally in each of four directions and separated at 90°. In this way a succession of obstructions are placed in the path of the grain, and these 95 obstructions are so arranged as to lie in a helical path. Such a device has been found to operate successfully in producing the desired grain movement without stoppage whereas a helically twisted wire has been 100 found to result in wedging. Either the indentations 26 in the pipe or the central baffle wire with its laterally projecting portions, as indicated in Figure 4, may be used alternatively or together. Of course, where both 105 these features are employed together, the agitation of the grain, and also its retardation, will be greater than where either feature is employed individually.

Beneath the drum the grain is discharged 110 from pipes 16, 17, and 18 in a large number of streams which, due to the arrangement of the pipes as aforesaid, are disposed in annular concentric series. If these streams were merely collected in a single funnel and led to 115 a discharge pipe, the result would be that those conduits discharging nearest the center of the funnel would have a rate of flow vastly greater than those conduits of the outer annular series. In order to equalize the flow, 120 of grain through all of the conduits the series of baffles hereinafter to be described has been devised.

Immediately above the outlet or discharge pipe 31 is a large funnel 32. This funnel 125 need not be physically connected with the remainder of the device. Discharging into funnel 32 and immediately thereabove is a similar funnel 33 which is removably supported from the drum 12. The supporting 130

means preferably includes the annular bent plates 34 connected with the funnel and provided with lateral opening slots 35 which receive suitable bolts 36 projecting radially from the drum. When the nuts 37 are loosened, funnel 33 may be rotated slightly to a position for its release downwardly away from the drum.

In funnel 33 is a frusto-conical baffle 40 having a cylindrically formed upper portion 41. This baffle extends to a point closely adjacent the head 14 of the heating drum whereby to prevent any grain issuing from pipes 16, 17, and 18 from finding its way down the center of the funnel. The frusto-conical baffle may be carried directly from the wall of the funnel through the medium of interposed bracket members 42 of L-shaped cross section. These bracket members may be secured to the wall of the funnel by welding or riveting in such a way that their upturned portions 42' will contact marginally with the lower periphery of baffle 40.

Bracket elements 44, similar to brackets 42, may be utilized to carry from baffle 40 an intermediate baffle 45. Baffle 45 comprises an annular element of triangular cross section. Its peak 46 is positioned immediately beneath each pipe 17 of the central annular series. The arrangement is such that grain issuing from each pipe 18 will contact with the wall of the funnel 33 and will be directed inwardly. Grain issuing from each pipe 16 will contact with the wall of baffle 40 and will be directed outwardly. The stream of grain issuing from each pipe 17 will be divided and a portion thereof will be diverted outwardly to mingle with grain flowing from pipe 18, whereas another portion thereof will be diverted inwardly to mingle with grain flowing from pipe 16. All of the grain must now pass between the outer periphery of baffle 40 and the wall of funnel 33. Obviously, any number of annular rows of grain delivery pipes similar to those indicated at 16, 17, and 18 may be employed successfully if a corresponding number of baffle elements is arranged after the principle stated above to ensure that grain issuing from each such row of pipes will have the same distance of travel and the same resistance to movement as the grain issuing from each other pipe.

From the annular space provided between the parts above mentioned the grain issues in a single annular stream. By way of further ensuring uniformity of flow, an additional baffle or baffles may be provided as indicated at 48, such baffle being adjustably supported from funnel 33 by bolts 49 extending through the wall of funnel 33 and through the suitably apertured extremity of bracket 52. Above and below the bracket each such bolt is provided with nuts 49a

whereby it may be adjusted vertically with reference to the bracket 52. The bolts 49 and brackets 52 will be provided in such numbers as are necessary for the support of cone 48 and for its convenient adjustment. It has been found that occasionally conditions are such that grain flow will take place more rapidly through the pipes on one side of the drum than through the pipes on the other side. To equalize such flow an adjustment of the cone shaped baffle 48 is made, whereby the margin of the baffle is brought closer or farther from the wall or funnel 33 to restrict or enlarge the opening for grain flow.

For the purpose of controlling delivery from funnel 33 I provide a valve 50 which comprises an inverted cone carried by L-shaped rods 51. Arms of bracket 52 project laterally from funnel 33 and are apertured to receive the upright portions of rods 51, said rods are preferably threaded and carry nuts 53 which rest upon arms 52 to support the cone valve 50 adjustably with reference to the outlet of funnel 33. Grain issuing from the outlet of funnel 33 will flow outwardly into funnel 32 in substantially the manner indicated in broken lines. It will there be exposed, and a thermometer imbedded in the stream of the grain issuing from funnel 33 will accurately indicate the temperature of said grain. This temperature may be varied in the manner indicated above.

When the grain is heated it may give off moisture,—either the natural moisture of the grain or moisture which has been added to it, as in the practice of the method disclosed in the Letters Patent issued to Peter Provost above identified. If it is desired to dry grain in its passage through the machine herein disclosed, such moisture can be removed by opening damper 22 in pipe 21, thereby permitting the heated air from the interior of baffle 40 to rise upwardly through pipes 15 to the interior of cone 20 and thence outwardly through pipe 21. Obviously, such air will carry with it moisture given off by the grain. If, on the other hand, it is desired to maintain the grain in the condition in which it is received, the damper 22 can be closed and circulation in pipe 21 may thereby be impeded to any desired extent or may be wholly stopped. If there is no air circulation through the interior of the device no moisture can escape therefrom other than that which is carried by the grain. Obviously the damper 22 will also serve to some degree to regulate the temperature at cap 20, since, if a slight circulation of air is permitted, cap 20 will rapidly become the hottest part of the drum.

It will readily be seen from the foregoing description of the series of baffles within funnel 33 that means has been provided for

equalizing the flow of grain through the several passages 16, 17, and 18. It will be seen, furthermore, that this equalization of flow is brought about without seriously impeding or retarding the flow of grain through any one passage. The baffles act, for the most part, to change the direction of flow of grain and thereby to equalize the distance travelled by grain from each pipe rather than to obstruct the flow of grain in the sense in which a valve obstructs the passage of material through a conduit controlled thereby.

I claim:

1. In a device of the character described, the combination with a heating drum having passages for grain extending symmetrically therethrough, of a steam pipe provided with branches entering said drum at symmetrically spaced points, whereby to equalize steam flow and temperatures to which grain in said passages is subject.

2. In a device of the character described, the combination with a heating drum having annular series of symmetrically spaced pipes extending therethrough, of baffle means for equalizing flow through said pipes, and steam pipes communicating with said drum at a plurality of points symmetrically spaced, whereby to render substantially uniform the temperatures to which material in said pipes are subject in passing therethrough.

3. In a device of the character described, the combination with a heating drum having a plurality of conduits extending in axial direction therethrough and at a plurality of radial distances from the center thereof, of a receptacle associated with said drum and having a wall downwardly converging to an outlet port, said conduits being adapted to discharge into said receptacle at differing distances from the wall thereof, and a set of baffles supported within said receptacle in operative position to divert material issuing from selected conduits, the amount of baffle-induced diversion being greater with respect to conduits comparatively remote from the wall of said receptacle than with respect to conduits adjacent said wall.

4. In a device of the character described, the combination with a heating drum having annular series of symmetrically spaced pipes extending therethrough, of baffle means for equalizing flow through said pipes, and steam pipes communicating with said drum at a plurality of points symmetrically spaced, whereby to render substantially uniform the temperatures to which material in said pipes are subject in passing therethrough, said pipes comprising a main, and branch passages of substantially equal length.

5. In a device of the character described, the combination with a heating drum having

annular series of symmetrically spaced pipes extending therethrough, of baffle means for equalizing flow through said pipes, and steam pipes communicating with said drum at a plurality of points symmetrically spaced, whereby to render substantially uniform the temperatures to which material in said pipes are subject in passing therethrough, said pipes comprising a main, branch pipes leading to opposite points with respect to said drum, and sub-branch pipes of substantially equal length diverging from said points and communicating with said drum at points substantially uniformly and symmetrically spaced about the periphery of said drum.

6. In a device of the character described, the combination with a heating drum, of concentric annular series of pipes extending through said drum, a funnel-shaped receptacle positioned beneath said drum and arranged to receive material issuing from said pipes, and an annular baffle disposed beneath the pipes of one of said series and adapted to retard the flow of material through the pipes of said series, and a second baffle disposed interiorly of said first baffle and having a downwardly and outwardly flaring portion; said last mentioned baffle being adapted to divert material from an additional series of said pipes.

7. In a device of the character described, the combination with a drum, of three annular series of pipes extending therethrough and a collecting device associated with said drum and disposed to receive material issuing from said pipes, said collecting device comprising a converging annular exterior wall, and a diverging annular interior wall terminating in a circular periphery spaced from said exterior wall.

8. In a device of the character described, the combination with a drum, of three annular series of pipes extending therethrough and a collecting device associated with said drum and disposed to receive material issuing from said pipes, said collecting device comprising a converging annular exterior wall, a diverging annular interior wall terminating in a circular periphery spaced from said exterior wall, and an intermediate baffle disposed immediately beneath the intermediate series of pipes and comprising an annulus adapted to divert material issuing from said pipe.

9. In a device of the character described, the combination with a drum, of three annular series of pipes extending therethrough and a collecting device associated with said drum and disposed to receive material issuing from said pipes, said collecting device comprising a converging annular exterior wall, a diverging annular interior wall terminating in a circular space from said exterior wall, and an intermediate baffle dis-

posed immediately beneath the intermediate series of pipes and comprising an annulus adapted to divert material issuing from said pipe, said annulus being of triangular cross section with its apex uppermost, whereby to divert material from said intermediate series of pipes both inwardly and outwardly.

10. In a device of the character described, the combination with a heating drum, of three annular series of pipes extending therethrough, an annular wall conforming at its upper margin with the periphery of said drum and converging downwardly therefrom to an outlet port, a frusto-conical wall positioned interiorly of said first mentioned wall and supported at a spaced interval therefrom, whereby to provide an annular passage, said passage being disposed substantially beneath the intermediate series 20 of said pipes, and an annular baffle supported from said frusto-conical wall substantially above said passage and between said intermediate series of pipes and said passage, said walls and said baffle being adapted to equalize resistance to flow through the pipes of each of said series.

11. In a device of the character described, the combination with a heating drum having a plurality of pipes extending therethrough at various radial distances from its center, of a detachable collecting device normally supported from said drum and comprising walls downwardly converging to a port, together with baffle plates supported from said walls and arranged to equalize substantially the distance of travel to said port of grain issuing from each of said pipes, whereby to equalize the flow of grain through said pipes.

12. In a device of the character described, the combination with a heating drum having a plurality of annular series of pipes extending therethrough, of collecting means comprising downwardly converging walls positioned to receive material from said pipes and adapted to guide material from the outer and innermost of said series toward a circular port positioned substantially beneath an intermediate series, said walls being spaced to provide such a port, and baffle means interposed between said intermediate series and said port, whereby to obstruct direct flow and substantially to equalize the distance of material travel between each of said pipes and said port.

13. In a device of the character described, the combination with a heating drum provided with a downwardly converging wall having a discharge port, of valve means controlling said port, and a funnel-shaped receptacle positioned immediately beneath said port and adapted to receive material issuing therefrom, said receptacle being connected with a discharge pipe and being

spaced from said port, whereby to permit inspection of such material.

14. In a device of the character described, the combination with a heating drum, of a plurality of series of pipes extending through said drum and opening outwardly from the heads thereof, a supply conduit having a discharge portion peripherally corresponding with the upper head of said drum, a receptacle having downwardly converging walls and peripherally corresponding at its upper end with the lower head of said drum, a conical cap centrally disposed on the upper head of said drum and arranged to divert material entering through said conduit away from a plurality of pipes adjacent the center of said drum, and a vent pipe connected with said cap and in communication through the pipes covered by said cap with said receptacle.

15. In a device of the character described, the combination with a heating drum, of a plurality of series of pipes extending through said drum and opening outwardly from the heads thereof, a supply conduit having a discharge portion peripherally corresponding with the upper head of said drum, a receptacle having downwardly converging walls and peripherally corresponding at its upper end with the lower head of said drum, a conical cap centrally disposed on the upper head of said drum and arranged to divert material entering through said conduit away from a plurality of pipes adjacent the center of said drum, and a vent pipe connected with said cap and in communication through the pipes covered by said cap with said receptacle, said vent pipe being controlled by a damper, whereby to regulate humidity in said receptacle.

16. In a device of the character described, a grain conduit provided with baffles comprising transversely elongated vertically staggered and inwardly extending protuberances in its walls.

17. In a device of the character described, the combination with a plurality of rows of grain outlets, of baffle means providing inclined paths of equal length to a common point from the outlets of each such row, and means for retarding grain flow from certain of said outlets proportionately to grain flow from others of said outlets.

18. In a device of the character described, the combination with a heating drum and grain conduits extending therethrough, of a receptacle adapted to receive grain from said conduits, and a member adjustable within said receptacle in the path of grain issuing from certain of said conduits and to and from a wall of said receptacle, whereby to restrict or enlarge the area for grain flow from certain of said conduits and to retard or accelerate the flow through said conduits

with reference to flow through others of said conduits.

19. In a device of the character described, the combination with a plurality of annular series of conduits and means for providing equal paths of delivery from radially adjacent conduits of the several series, of means for retarding flow at one side of said

series with reference to flow at the opposite side of said series, said means comprising a grain passage adapted to receive grain from all of said conduits and having therein a flow obstructing member adjustable to restrict given portions of said passage with reference to other portions.

GEORGE A. ROCKBURG.
